COMBINED STOVE AND LAMP

Henry Henderson Morton, London, England, assignor to
The Savoy Hotel Limited, London, England

Application April 7, 1958, Serial No. 50,364

Term of patent 14 years

(Cl. D81—10)

Fig. 1.

Fig. 2.

Fig. 3.

Fig. 4.

Figure 1 is a perspective view of a combined stove and lamp showing my new design; Figure 2 is a perspective view thereof taken from the opposite side and bottom; Figure 3 is a top plan view of the combined stove and lamp; and Figure 4 is a bottom plan view thereof.

I claim:

The ornamental design for a combined stove and lamp, as shown.
